P. MYERS

WHEELED TOY

Filed Sept. 2, 1924

Inventor:

Philip Myers

by Albert Scheibh
Attorney

UNITED STATES PATENT OFFICE.

PHILIP MYERS, OF GLENVIEW, ILLINOIS, ASSIGNOR TO THE TOY TINKERS, INC., OF EVANSTON, ILLINOIS, A CORPORATION OF ILLINOIS.

DESIGN FOR A WHEELED TOY.

Application filed September 2, 1924. Serial No. 10,634. Term of patent 14 years.

To all whom it may concern:

Be it known that I, PHILIP MYERS, a citizen of the United States, residing at Glenview, in the county of Cook and State of Illinois, have invented a new, original, and ornamental Design for Wheeled Toy, of which the following is a specification, reference being had to the accompanying drawing, forming part thereof.

The drawing is a perspective view of a wheeled toy, showing my new design.

I claim:

The ornamental design for a wheeled toy, as shown.

PHILIP MYERS.
